INVENTOR

George W. Lawson
By David Arthur
Atty:

UNITED STATES PATENT OFFICE.

GEORGE W. LAWSON, OF BROOKLYN, NEW YORK.

ELECTRIC BATH.

SPECIFICATION forming part of Letters Patent No. 257,875, dated May 16, 1882.

Application filed January 24, 1882. (No model.)

To all whom it may concern:

Be it known that I, GEORGE W. LAWSON, of Brooklyn, county of Kings, and State of New York, have invented certain new and useful Improvements in Electric Baths; and I do hereby declare that the following is a full, clear, and exact description thereof, reference being had to the accompanying drawings, and to the letters of reference marked theron, making a part of this specification.

My invention relates to an improved apparatus for generating and applying in a bath electricity and remedial vapors for hygienic purposes.

It consists in the construction of a bath-chamber wherein the resultant electric current obtained by the application of cold water to one end of each of the elements in a thermo-electric pile whose opposite ends are simultaneously heated by a suitable calorific device is conducted to the person of the bather, while the heat employed in exciting the battery is utilized in elevating the temperature of the bath and in the generation of vapors for use therein.

Figure 1 is a central vertical section of my improved thermo-electric and vapor bath, and Fig. 2 a horizontal section through the thermo-electric generator detached and drawn upon an enlarged scale.

A A are the sides of a chamber adapted to constitute the bathing-room. It is made of such a height as that a person standing therein shall be wholly concealed thereby. It is made water and steam tight, and its bottom, sloping toward a drain-pipe, B, is fitted with a slotted or perforated floor, C. An adjustable stool or seat, D, is fitted upon one side thereof and a foot-rest, E, upon the opposite side within easy reach of a person sitting upon the seat D. This foot-rest consists of a hollow copper vessel, which it is desired shall be filled with hot water, when in use, to maintain a constant heat at the feet of the bather. A plate or panel, F, is fitted upon springs a a, back of the seat D, to afford an easy yielding adjustable support to the back of the person seated upon the stool. The back plate, F, is partially covered by a zinc plate, e, to extend almost the entire length of the spine of the

bather when leaning back against it, and which, by a wire connecting it with the battery, is made to constitute one of its poles or elements, the copper foot-rest being in like manner constituted the opposite pole or element of the same battery.

A transverse partition, G, within the chamber A A serves to completely close and shut in the chamber from above. This partition is placed at about the level of the neck of a person sitting upon the seat D. The partition extends from the side back of the seat horizontally to a point over the latter, and slopes thence at an angle downward toward the front of the bath. An aperture, H, is cut in the partition immediately over the stool D, of a size adapted to closely encircle the neck of a person, and the partition is divided in a line passing centrally through the aperture H, parallel to the rear side of the chamber, and again in lines at b and c, parallel to the first. The sections H b and b c are hinged together, and the latter to the front strip, d, of the partition, so that they may be opened up and folded over, as shown in dotted lines, to permit the bather to enter and stand up in the bath, as required.

Windows J J are fitted in the sides of the chamber above its transverse partition, to be thrown open after the bather is inclosed in the bath to admit of a free circulation of air above his head as it projects through the opening at H. The windows may be glazed with ground or stained glass and fitted with shades i. i. A side door affords entrance to the bath.

A shower, K, and a flexible pipe and nozzle, L, supplied with hot and cold water and governed by cocks g g g g, placed within easy reach of the bather, furnish the conveniences of a shower and douche bath.

In front of the bathing-apartment thus constructed I place my thermo-electric and vapor-generating apparatus. The improved thermo-electric battery consists of a series of alternate copper and zinc strips M M', arranged side by side, parallel to each other, one end of each being bent to dip into a vessel, P, of running water, leaving its opposite longer end to project therefrom horizontally at a right angle therewith (see Fig. 1) over a series of gas-burners, N N, or other equivalent calorific de-

vice. The positive and negative strips $M M'$ are connected in pairs alternately at their opposite extremities by coupling plates or strips $m m$, so as to unite the entire series into a single continuous metallic conductor, following the entire length of each of the alternate zinc and copper plates, and which, commencing with a copper plate, M , will terminate with a zinc plate, M' , each plate in the series being subjected simultaneously and continuously to the heat of the burners at one end and the coolness of the water at the other. The battery $M M' P N$ is inclosed within a suitable case, $R R'$, closed by a hinged lid, R' . The vessel P is constantly supplied with a stream of cold running water through suitable supply and discharge pipes, $P' P''$, Fig. 2. Free communication is established between the interior of the battery-case and the bottom of the bath-chamber A by means of an extended opening, S . The poles of the battery are connected by wires, the one with the zinc plate forming the back of the seat D and the other with the copper foot-rest E , or vice versa, if desired.

25 A copper tank, T , is fitted upon the inner under side of the lid or cover of the battery-chamber R , and is provided with an opening, t , closed by a suitable stopper, through which the tank may be filled with water. This stopper is fitted upon its inner side with a perforated cup for holding the drugs with which it may be desired to charge the water for medicating purposes.

35 A pipe, T' , fitted within the bath-chamber A and terminating in a suitable nozzle beneath the bather's seat, is coupled by a flexible connecting-pipe, T'' , with the top of the tank T , so that vapor generated in said tank may be discharged into the bottom of the bath-chamber. The pipe T' is controlled by a valve, h , actuated by a pull, h' , within reach of the bather's hand when seated.

Air is admitted to the battery-chamber R , 45 and through it to the bath-chamber A , by means of openings $U U'$, closed by suitable doors. One or more draft-pipes, V , each governed by a damper, are placed in the rear of the bath-chamber, under the transverse partition therein, to provide for a discharge of vapors therefrom.

The apparatus is rendered yet more complete for practical purposes by combining therewith a galvanic battery, W , supported 55 upon brackets outside of the chamber, and whose poles are connected with electrodes $W' W'$, placed within the chamber in easy reach of the bather.

A thermometer, Y , is placed so as to indicate to the bather, when seated with his body inclosed by the transverse partition G , the temperature of the lower compartment.

In the use of my improved apparatus the thermal battery is brought into operation by 65 causing a flow of water through the cooling-vessel P and lighting the burners $N N'$. The

difference of temperature thus produced in opposite ends of the connected positive and negative strips $M M'$ generates a mild yet potent electric current, possessing peculiarly beneficial hygienic properties when caused to circulate through the body. The bather, upon sitting down upon the seat D , putting his feet upon the foot-rest E and leaning back against the plate F will close the circuit from the 70 battery and the current will pass through his body and limbs. If, now, the folding partition G be shut down encircling the neck of the bather and completely inclosing the lower compartment in which he is seated, the heat 75 of the burners in the battery-chamber will rapidly elevate the temperature in said lower compartment until a gentle perspiration will be induced, facilitating the flow and healthful action of the electric current. If a sulphur or 80 other form of medicated hot-air bath is required, the sulphur or other drug is placed in the battery-chamber, over its burners, so that the heat thereof will quickly produce the desired fumes, which, escaping thence, will pass 85 into and fill the lower compartment of the bath-chamber. If a steam or vapor bath is wanted, the tank T is filled with water, or with any description of herbal infusion or medicinal tincture required, and being heated by the burners 90 $N N'$ the vapor generated therein will be discharged through the pipe T into the bath-chamber. The thermo-electric current is designed to remain in constant action, whether the hot air or dry fumes from the battery 95 chamber or the vapors from the tank T be used therewith or not; but the action of the current is arrested at pleasure by removing the feet from the rest E .

By means of the electrodes $W' W'$ any desired special application of a galvanic current may be made by the bather during his bath. The temperature of the bath may be lowered by the bather at pleasure by means of cords which control the dampers U in the battery-chamber. The douche and shower, hot, cold, or tempered, as he may desire, are at his command at the close of his electric hot-air or vapor bath to complete the same.

The elements of the battery may consist of 115 antimony and bismuth, or any of the alloys which have been found useful in the production of a thermo-electric pile, instead of copper and zinc.

It is evident that the various applications of 120 the bath may be made and controlled from without by an attendant.

What I claim as new, and desire to secure by Letters Patent, is—

1. The combination of a bath-chamber, A , a 125 separate communicating chamber R , burners N , placed therein, adapted to heat said chambers, an electro-thermal pile or battery, $M M'$, adapted to be heated continuously on one side by said burners, and to be cooled on the other 130 by a continuous current of water, and a back plate, F , and foot-rest E , constituting the elec-

trodes of said battery, all substantially as and for the purpose herein set forth.

2. The combination, with an electro-thermal pile or battery, M M', a back plate F, and foot-rest E, constituting its electrodes, and a bath-chamber, A, inclosing said electrodes, of a hot-water and vapor-generating tank, T, adapted to be heated by the calorific device of the battery, and communicating with the bath-cham-

ber by a connecting-pipe, T', substantially as 10 and for the purpose herein set forth.

In testimony whereof I have signed my name to this specification in the presence of two subscribing witnesses.

GEO. W. LAWSON.
